(57) **CLAIM**

The ornamental design for a cradle for supporting a monitoring camera, as shown and described.

DESCRIPTION

FIG. 1 is a front elevational view of a cradle for supporting a monitoring camera showing our new design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof;

FIG. 7 is a perspective view thereof; and,

FIG. 8 is a perspective view thereof in position of use with a monitoring camera shown by double dotted lines.

The broken line showing of a monitoring camera is for illustrative purposes only and forms no part of the claimed design.
